Inventor

Heinrich E. Jones

UNITED STATES PATENT OFFICE.

MELVILLE D. JONES, OF BOSTON, MASSACHUSETTS.

DESIGN FOR IRON POST.

Specification forming part of Design No. 5,378, dated November 21, 1871.

To all whom it may concern:

Be it known that I, MELVILLE D. JONES, of Boston, county of Suffolk and State of Massachusetts, have invented and produced a new and original Design for an Iron Post, of which the following is a specification:

The nature of my design is fully represented

in the accompanying drawing, to which reference is made.

I claim as my invention—

The design for an iron post, as shown.

Witnesses: MELVILLE D. JONES.

HENRY A. MAY,

JOHN MAY.
